CARBURETOR

Scott F. Hunt, South Bend, Ind., assignor to Bendix Aviation Corporation, South Bend, Ind., a corporation of Delaware

Application January 23, 1934, Serial No. 707,942

8 Claims. (Cl. 123—119)

This invention relates to carburetors, and more particularly to automatic choke control mechanism, and is an improvement on the mechanism disclosed in my copending application No. 630,274, filed August 24, 1932.

In the operation of internal-combustion engines using liquid fuel, it is customary to incorporate some kind of choke valve in the carburetor for the purpose of enriching the mixture to start the engine and for operation while the engine is heating up. Since it is impossible for the operator to determine the most advantageous mixture setting to give greatest efficiency, and since the mixture ratio must be changed gradually as the engine warms up, it has been found that better results may be obtained by the use of automatic choke control, employing the engine variables, manifold suction and temperature. It is thus possible to provide a mixture that will be consistent with the requirements of the engine at all times, and therefore give greater efficiency.

Another feature of this invention has to do with a throttle-cracking and fast-idle mechanism.

It is a further object of this invention to provide an improved choke valve and fast-idle mechanism which will operate automatically to prevent overchoking of the engine while starting, and provide a suitable mixture for warming up purposes.

A further object is to provide mechanism whereby the choke valve may be positively opened to eject an excess charge of fuel from the cylinders in case the engine should become flooded.

The above and other novel features of this invention will appear more fully hereinafter from the following detailed description when taken in connection with the accompanying drawing. It is understood, however, that the drawing is submitted merely for the purpose of illustrating the invention and is not intended to limit the same, the scope of the invention being defined by the appended claims.

In the drawing, wherein similar reference characters refer to similar parts throughout the several views,

Figure 1 is a vertical section of a device embodying the invention;

Figure 2 is a section on line 2—2 of Figure 1;

Figure 3 is a section on line 3—3 of Figure 2; and

Figure 4 is a section on line 4—4 of Figure 2.

Referring more particularly to Figure 1, there is shown for purposes of illustrating this invention a common type of down-draft carburetor

having an upper body section 10 and a lower body section 12 fixed to the intake manifold 14. The thermostat control mechanism 16 for actuating the choke valve is mounted on the exhaust pipe 17 or in any other location where it will be subjected to the heat generated by the engine in its operation.

Referring to the carburetor, there is shown a choke valve comprising an unbalanced disc 18 mounted on a shaft 20, which is journaled in the walls of the upper body section 10 adjacent the air horn 22. A fuel nozzle 24 is positioned to discharge fuel at the most restricted section of a primary venturi 26, which in turn discharges at the most restricted section of a secondary venturi 28. Below venturi 28 a butterfly throttle valve 30 of known construction, adapted to control the flow of mixture into the intake manifold 14, is mounted on a shaft 32, which is journaled in the walls of the lower body section 12.

Fixed to choke valve shaft 20 by means of a set screw 33 is a crank 34 which is connected by a link 36 to a second crank 38 fixed to shaft 40 of the thermostat control mechanism 16, so that shaft 40 and choke valve 18 operate together. A spiral bimetallic spring 42 has its inner end fixed to shaft 40, its other end being hooked to engage a suitable pin 44 fixed in housing 46 so that the thermostat may urge choke valve 18 toward closed position when the engine is below normal operating temperatures.

A double-armed stop member 47 fixed to housing 46 is used as an index in assembling the automatic choke device. The device is assembled at a specified temperature by closing choke valve 18, moving crank 38 into contact with the stop 47 nearest the carburetor, tightening set screw 33, thereby clamping crank 34 to shaft 20. The other stop 47 may be used as an index for adjustment should it be found desirable to assemble the thermostat on the opposite side of the carburetor or in inverted position.

A housing 48 (Figure 2), cast integral with the lower body section 12 above throttle valve 30, accommodates a vacuum actuated piston 50 slideable in a cylinder 52 which communicates with the carbureting passage posterior to the throttle through passages 54 and assists in moving the choke valve 18 from the closed position when the engine starts as described below, by rotating arm 56, the end of which fits in a slot 57 in the upper end of piston 50.

Arm 56 is rotatably mounted on a shaft 58, which is journaled in a plate 60 which closes housing 48. The arm 56 is provided with an ear

62 which is adapted to engage a pin 64 fixed in shaft 58, so that shaft 58 is rotated in a counterclockwise direction as piston 50 is drawn downwardly in cylinder 52.

5 Shaft 58 also has rotatably mounted thereon a stop member 66 provided with several stepped surfaces 68 of suitable number and size and adapted to engage an adjusting screw 70 carried by one end of an arm 72 fixed to throttle shaft 10 32. Member 66 is yieldingly urged in the counterclockwise direction by a spring 74 which connects it with an ear 76 formed on a lever 78, which is fixed to the shaft 58. One end of lever 78 connects through a link 80 with an arm 82 15 fixed to choke shaft 20 at the opposite side of the air horn from crank 34. The other end of lever 78 is provided with an ear 84 to engage a shoulder 86 formed on stop member 66 to rotate said member in the clockwise direction as choke valve 18 closes, thereby causing adjusting screw 70, when the throttle is subsequently closed, to engage one of the higher steps 68, producing a faster idle. The throttle is controlled by manual actuating mechanism 92, of usual construction, and is yieldingly urged toward closed position by the usual throttle return spring, indicated diagrammatically at 93. When the throttle is moved to its fully opened position, an ear 88 on arm 72 engages the under surface of a projection 90 on lever 78, thus rotating lever 78 in the counterclockwise direction and moving the choke valve to partially opened position against the force of thermostatic spring 42, as shown in Figure 1. It is thus apparent that should the engine become flooded the operator may partially open the choke valve to permit the excess fuel to be drawn out.

The operation is as follows: Assuming that the engine has been fully warmed up and is stopped and allowed to cool, thermostatic spring 42 will exert a gradually increasing force tending to rotate shaft 40 in the counterclockwise direction, and urging choke valve 18 in the closing direction by means of the above described mechanism consisting of link 36 and cranks 34 and 38.

As choke valve 18 moves toward closed position, arm 82, fixed to choke shaft 20, moves in the clockwise direction and by means of link 80 rotates lever 78 in the clockwise direction. The throttle is of course in fully closed position during this operation. As lever 78 rotates, it acts through ear 84 to rotate stop member 66 with it until the lowermost of stepped surfaces 68 contacts the lateral surface of adjusting screw 70, whereupon further movement of stop member 66 and lever 78 is arrested.

When the operator wishes to start the engine he opens the throttle a small amount, thereby drawing adjusting screw 70 out of contact with the stepped surface 68 and permitting thermostatic spring 42 to move choke valve 18 to closed position. The operator then turns the ignition switch and starts the engine.

As soon as the engine begins to fire, suction will be transmitted from the intake manifold 14 to cylinder 52 through ports 54, drawing piston 50 and arm 66 downward. As arm 66 rotates on shaft 58, ear 62 engages pin 64 and rotates shaft 58 and member 66 which, through the action of shoulder 86 contacting ear 84, carries with it lever 78. Lever 78, through link 80 and arm 82, opens choke valve 18 a small amount against the resistance offered by thermostat spring 42, thus admitting air to prevent overchoking of the engine. In this position, choke valve 18 is free to open somewhat further under the varying force of suc-

tion in the carburetor, and against the force exerted by springs 42 and 74. If the throttle actuating mechanism 92 is at closed position during such further opening movement of the choke valve, however, stop member 66 will be held in fixed position by the friction between screw 70 and the cooperating stepped surface 68. A fast idle is therefore maintained during this period as adjusting screw 70 engages one of the higher steps 68 and prevents the throttle from fully closing.

As the engine begins to warm up, bimetallic spring 42 tends to coil more closely upon itself and exerts a decreasing counterclockwise force on shaft 40, allowing choke valve 18 to open more and more widely under the influence of suction 15 in the carburetor.

If the operator accelerates the engine, screw 70 disengages steps 68 and stop member 66 is rotated in the counterclockwise direction by spring 74 so that when the accelerator pedal is released 20 screw 70 may engage one of the lower steps 68. It is thus apparent that several progressively slower idling speeds are provided as the engine warms up.

When the engine is thoroughly warmed up, 25 the free end of spring 42 disengages pin 44 and therefore exerts no force tending to close choke valve 18, which will remain in full open position, and adjusting screw 70 will engage the lowest of steps 68 thereby producing a normal or slow 30 idle speed of the engine.

If for any reason the engine should become flooded, the operator will fully open the throttle. As the throttle approaches full open position the ear 88 on arm 72 engages the projection 90 of 35 lever 78 and slides thereon, rotating lever 78 in the counterclockwise direction and opening choke valve 18 by means of the above described mechanism comprising link 80 and arm 82, so that the pumping action of the engine may be applied to 40 draw the excess raw fuel from the cylinders.

It is expressly understood that the scope of this invention is to be limited by nothing appearing herein except the following claims.

I claim:

1. In a carburetor, a pressure responsive air inlet valve, thermostatic means influencing the movement of the same, a throttle, a stop member fixed thereto, a vacuum controlled motor, and a positive connection for transmitting force 50 from said motor to said air inlet valve, said connection including a member having a plurality of discrete stop surfaces movable into the path of said stop member to limit the closing movement of the throttle.

2. In a carburetor, a pressure responsive choke valve, temperature responsive means urging the choke valve toward closed position when cold, a throttle, a stop member fixed thereto, a motor controlled by vacuum posterior to the throttle, 60 and a connection for transmitting force from said motor to the choke valve but incapable of transmitting force from the choke valve to said motor, said connection including a rotary member having several discrete surfaces movable into 65 the path of said stop member to limit in varying degree the closing movement of the throttle.

3. The invention defined in claim 1, wherein the vacuum controlled motor comprises a cylinder fixed to the carburetor and communicating 70 therewith posterior to the throttle.

4. In a carburetor, a carbureting passage, a pressure responsive valve controlling the inlet of said carbureting passage, yielding means influencing the movement of the pressure respon-

sive valve, a throttle controlling the outlet of said carbureting passage, a stop member carried thereby, a motor controlled by vacuum posterior to the throttle, a connection for transmitting force from said motor to the pressure responsive valve, said connection including an idle-control member having a plurality of discrete surfaces movable into the path of said stop member to variably limit the closing movement of the throttle, and yielding means connecting said idle-control member to another portion of said connection.

5. In a carburetor, a carbureting passage, a choke valve controlling the inlet of said carbureting passage, temperature responsive means 15 urging the choke valve closed when cold, a throttle controlling the outlet of said carbureting passage, a stop member carried thereby, a suction-controlled motor, and a connection for transmitting force from said motor to the choke valve, 20 said connection including an idle-control member rotatably mounted adjacent the stop member and cooperating therewith to variably limit the closing movement of the throttle, said idle-control member being yieldingly connected to another portion of said connection.

6. The invention defined in claim 5, including means coacting with said connection when the throttle is moved to open position to partially open the choke valve.

30 7. A carburetor of the character described, comprising a body having a passageway therethrough with air and fuel inlets, a manually operable throttle valve having a shaft and controlling flow through said passageway and being 35 freely movable toward open position, said valve being movable to closed engine idling position at the will of the engine operator to control engine idling operation, an adjustable stop member

for variably limiting the extent of closing movement of said valve through a range of engine idling positions, said stop member comprising a rotatable member eccentrically mounted on said body and having a plurality of discrete surfaces, said stop member and said throttle shaft being closely adjacent each other, an arm rigidly secured to and movable with said valve, and a stop member on said arm and engageable with said rotatable member on valve closing movement to limit throttle valve closing movement.

8. A carburetor of the character described, comprising a body having a passageway therethrough with air and fuel inlets, a manually operable throttle valve controlling flow through 15 said passageway and freely movable toward open position, said valve being movable to closed engine idling position at the will of the engine operator to control engine idling operation, an adjustable stop member for limiting the extent 20 of closing movement of said valve, said stop member comprising a member rotatably mounted on said body and having a peripheral surface non-circular about its center of rotation, means movable with said valve and engageable with said 25 peripheral surface on valve closing movement irrespective of the rotary position of said rotatable member, said stop member and said rotatable member engaging means being carried as a unit by said throttle valve containing body, a thermostat 30 responsive to engine temperature and operable at low temperatures to urge said rotatable member toward a position which permits a less degree of closing movement of said valve, an arm on said rotatable member, and means operatively 35 connecting said thermostat and said arm.

SCOTT F. HUNT.
